UNITED STATES PATENT OFFICE

WILLIAM J. WHATLEY, OF DALLAS, TEXAS

INTERNAL-COMBUSTION ENGINE

Application filed November 28, 1927. Serial No. 236,282.

This invention relates to certain new and useful improvements in internal combustion engines and the primary object thereof is to provide an engine which employs a multiplicity of cylinders arranged in line with a crank shaft having its cranks arranged throughout the entire circumference of the shaft in spaced regular order so that a direct downward drive of the shaft will occur with substantial continuity to thus derive not only a maximum of power but to also obtain smooth driving of the shaft.

In the drawings:—

Fig. 1 is a longitudinal sectional view of the invention;

Fig. 2 is a section on line 2—2 of Fig. 1, and

Fig. 3 is a view similar to Fig. 1, showing a modified form of the invention.

In the form of the invention illustrated in Fig. 1 of the drawings, eight cylinders 1 are employed which are provided with pistons 2 and piston rods 3. The cylinders 1 are arranged in a line parallel to the crank shaft 4. The crank shaft has cranks 5, 6, 7, 8, 9, 10, 11 and 12, one for each of the piston rods, the latter being connected to the rods by journal boxes 13. The adjacent cranks are connected by inclined parts 14, four in number.

By referring to Fig. 1 of the drawings, it will be noted that the cranks 5 etc., are located in varying relation to the longitudinal axis of the shaft and, as shown in Fig. 2, such cranks are arranged so that collectively they entirely surround the shaft in regular spaced order.

Thus by reference to Fig. 1, it will be noted that as the first cylinder to the right is at the limit of its idle or upstroke, the last cylinder is at the limit of its working or downstroke, while the intermediate cylinders occupy intermediate positions between the two extremes in regular steplike order as depicted in Fig. 1. With this construction and assemblage of the parts, it will be seen that the pistons will successively drive the shaft and

full direct downward strokes will be imparted to the shaft in successive order throughout its 360°, due to the cranks being disposed throughout the circumference of the shaft, as depicted in Fig. 2. The cylinders may be cast en bloc and are provided with

supporting arms 17 equipped with journal boxes 15 in which latter intermediate parts 16 of the shaft 4 are rotatably supported. The arms 17 are arranged at the ends of the cylinders and between each pair of adjacent cylinders so that five arms are accordingly employed. The shaft with the disclosure of Fig. 1 receives eight direct downward strokes in successive order.

In Fig. 3 a modified form of the invention is disclosed and wherein the cylinders are arranged in V-formation. In this form of the invention, there are sixteen cylinders employed, eight in a line, the two lines having the V-relation shown in Fig. 3. With this structure, each of the cranks of the shaft is provided with a double bearing for the two piston rods of the opposed cylinders, the cranks otherwise being arranged in a regular spaced order about the entire circumference of the shaft, consequently the shaft receives sixteen direct impulses instead of eight, as in the instance of Figs. 1 and 2. Obviously greater power is accordingly had and corresponding increased smoothness in the shaft drive, due to the impulses being imparted to the shaft at one-half of the distances in the instance of Fig. 1.

The firing of the cylinders is successive, i. e., the second following the first, the third the second, etc. In the V-type the cylinders are similarly fired, however, when the pistons of the cylinders on one side are on their working stroke, the pistons on the other side are on their idling or compression stroke.

Obviously the invention is susceptible of use with engines of any type, whether two or four cycle, the engine per se forming no part of the present invention.

What is claimed is:—

1. In an internal combustion engine, a series of aligned cylinders arranged in pairs and each having a piston and a piston rod therein, an integral crank shaft having spaced pairs of cranks which latter are disposed in equi-distantly spaced progressively circular order and are connected by intermediate inclined parts, said inclined parts being of greater diameter than that of the cranks to form end shoulders, journal boxes for the

piston rods connected thereto and having one side of their sides abutting the respective shoulders, connecting parts for adjacent pairs of the cranks extending across the space there-between and having shoulders engaging the opposite sides of the journal boxes, and journals for said connecting parts.

2. In an internal combustion engine, a series of aligned cylinders arranged in pairs and each having a piston and a piston rod therein, an integral crank shaft having spaced pairs of cranks which latter are disposed in equi-distantly spaced progressively circular order and are connected by intermediate inclined parts, means to connect the rods to the cranks, connecting parts for adjacent pairs of the cranks extending across the space there-between, and journals for said connecting parts.

20 In testimony whereof I affix my signature.
WM. J. WHATLEY.
